UNITED STATES PATENT OFFICE.

MAX AMS, OF NEW YORK, N. Y.

EVAPORATING APPARATUS.

SPECIFICATION forming part of Letters Patent No. 399,311, dated March 12, 1889.

Application filed November 12, 1888. Serial No. 290,585. (No model.)

To all whom it may concern:

Be it known that I, MAX AMS, of New York city, New York, have invented an Improved Evaporating Apparatus, of which the following is a specification.

This invention relates to an apparatus for cooking, evaporating, or concentrating various substances—for instance, fruit-juice and other articles of food, glycerine, &c.

10 The apparatus is so constructed that the vapors that arise from the substances that are being treated are continually drawn off, and so that such substances are kept continually in motion. Thus the evaporating process is 15 accelerated and burning is prevented.

The invention consists in the various features of improvement more fully pointed out in the claim.

In the accompanying drawings, Figure 1 is 20 a front elevation of my improved apparatus. Fig. 2 is a top view thereof with chamber *h* removed. Fig. 3 is an end view of Fig. 1, looking at its left-hand side and with the outer wall removed. Fig. 4 is a vertical transverse section through one of the evaporating troughs or vessels.

25 The letters *a a a a* represent a suitable series of troughs or vessels placed below and in front of one another, as shown in Fig. 3. Each trough is inclined—the first and third trough in one direction and the second and fourth trough in the opposite direction. Thus it will be seen that the lowermost end of any one trough is above the uppermost end of the 30 trough next below. Each trough is provided with a double bottom, *b*, to constitute a steam-chamber extending below the entire length of the trough. These steam-chambers communicate at one end with the steam-inlet pipes 35 *c* and at the other end with the steam-outlet pipes *c'*.

The troughs *a* are closed partially at each end by the end walls, *d*. These walls, however, do not extend to the top of the trough, 45 but only partly up, so as to leave an open space on top. These open spaces are indicated by the full black shading in Fig. 3. Through the end wall, *d*, there extends at the lowermost end of each trough a tube, *e*, that opens directly above a funnel, *f*, secured to a tube, *f'*, 50 at the uppermost end of each trough. Thus

the liquid that is being cooked, concentrated, or evaporated can flow continuously from the uppermost trough to the troughs next below, and can be finally drawn off from the discharge-tube *e'* at the bottom of the apparatus. Samples of the substance can at any time be taken at any of the tubes *e*, and thus the process can be kept under control.

55 Each trough *a* should be provided with a cover, *g*. At one end (right-hand end in Fig. 1) all the troughs are in direct communication with the atmosphere through the open end wall, *d*; but at the other end all the troughs open into a chamber, *h*. Within this chamber there is hung upon a shaft a fan-wheel, *i*, revolved by suitable power. This fan-wheel will draw the vapors or steam arising from the substances under treatment into the chamber *h*, from whence they escape into the free air 70 through the usual opening around the fan-wheel. The arrows in chamber *h* of Fig. 1 indicate the motion of the steam or vapors.

75 The operation of the apparatus will be readily understood. The substance to be cooked, concentrated, or evaporated is poured into the uppermost trough, and will flow from trough to trough until it is discharged through tube *e'*. Steam, being admitted into the double bottom, will act upon the flowing substance 80 and cook, evaporate, or concentrate it. During the process the vapors arising from the substance under treatment will be continually drawn off by the fan-wheel *i*. Thus the operation of cooking is greatly accelerated. 85 Moreover, as the substance under treatment is in continuous motion, it will not become burned at the bottom of the troughs.

What I claim is—

90 The combination of a series of communicating inclined troughs having double bottoms, covers, and steam inlet and discharge pipes, with open walls at one end and with a vapor-collecting chamber at the other end, into which the several troughs open, and with a fan-wheel 95 within said vapor-collecting chamber, substantially as specified.

MAX AMS.
